UNITED STATES PATENT OFFICE

WILLIAM HAMILTON DUNNE, OF TORONTO, ONTARIO, CANADA

ROLLER SKATE

Application filed August 25, 1928. Serial No. 301,986.

My invention relates to improvements in roller skates, and more particularly to extension skates having a toe plate and a heel plate, each carrying a roller truck, the said plates being slidable with respect to each other, and capable of being clamped in any desired position of adjustment. In skates of this character, a common and serious defect has been the buckling of the toe plate at its inner end or shank, by reason of the fact that the toe plate is slotted at this location to permit shank extensions of the heel plate to pass therethrough and lie against the underside of said toe plate. The principal object of my invention is to construct the toe plate so as to avoid the use of a slot therein for the purpose set forth, and thus strengthen the body of the skate and so lengthen the life thereof, and in the following specification and the drawings forming part thereof, I shall describe and illustrate my invention, and what I claim as new will be set forth in the claims forming part of this specification.

Fig. 1 is a plan of the underside of the body of the skate, and Fig. 2 is a plan of the topside thereof. Fig. 3 is a side elevation of Fig. 2, and Fig. 4 is a vertical longitudinal section on the line 4—4, Fig. 2. Figs. 5 and 6 are cross sections on the lines 5—5, and 6—6, respectively.

In the drawings, like characters of reference refer to the same parts.

2 is the toe plate, and this plate is integral-
ly provided with shank extensions 3 spaced apart.

4 is the heel plate, and this plate is also provided with shank extensions 5 spaced apart. Each plate is provided with a hanger stamping 6 having the usual tabs 7 to support the wheel trucks as is common in the art. These hanger stampings are provided with vertical flanges, portions of which serve as rivets 8 which are clamped in the said plates after the manner well-known in the art. There is nothing new in these hanger stampings, and they are so made that the vertical flanges 9 are spaced below their respective plates so as to permit the spaced shank extensions to pass between same and the plates as shown clearly in Fig. 4.

Riveted in the shank of the heel plate 4 is a pin 10 provided on its underside with a head 11 wider than the slot separating the shank extensions 3, and therefore the inner sides of these shank extensions are engaged by said head: this is a construction of course well-known. 12 is a bolt projecting through a hole 13 formed in the shank of the toe plate 2, the head 14 of this bolt is large enough to engage with the sides of the shank extensions 5. 15 is a stay through the upper end of which the bolt 12 passes, and this stay is secured to the pin 16 mounted in the front hanger stamping. A nut 17 screws on the lower end of said bolt, and it is by means of the parts just described that the skate is adjusted to different lengths and held in this adjusted position. This means of adjusting the skate and holding it in adjusted position of course is well-known.

To overcome the necessity of having to slot the shank of the toe plate 2, I stamp the side wings 18 of said toe plate above the rest of the surface, thus forming a channel from the dotted line 19 to the end of the toe plate, 75 and I house in this channel the shank extensions 5. The top surface of these shank extensions lies substantially in the same plane as the top surface of said wings. At the same time the wings 18 are formed I also stamp 80 above the bottom of said channel, lugs 20 near the extremity of the toe plate. These lugs are substantially of the same height as the wings 18, but they are spaced apart therefrom by channels 21, in which are located the 85 riveted ends of the pins 22, which pins are provided with wide heads 23 to support the jaws (not shown). Of course these jaws are those commonly employed to clamp the toe portion of the skate to the sole of the boot. 90

As will be seen clearly upon referring to Fig. 2, the outer sides or edges of the shank extensions 5 have an easy fit against the inner parallel sides of the wings 18 as well as the lugs 20, and therefore these shank extensions 95 are given lateral support thereby.

It is shown clearly in Fig. 4 that the top sides of the shank extensions 3 lie substantially in the same plane as the top of the channel separating the wings 18, and that said shank 100

extensions lie against the underside of the heel plate 4.

In order to give vertical support to the shank extensions 5 of the heel plate 4, I secure by means of the rivets 8 a plate 24 which bridges the channel extending longitudinally of said toe plate, and rests in contact with the upper surface of the wings 18. Of course this plate 24 permits of the free sliding movement of the shank extensions 5.

What I claim as my invention is:

1. A skate body comprising a heel plate longitudinally provided with spaced shank extensions; a toe plate also longitudinally provided with spaced shank extensions, and further provided with spaced side wings extending from approximately the shank forwardly for the desired distance, and a pair of spaced lugs, which lugs are also spaced apart from said wings, the said wings and lugs being stamped above the rest of the surface of said toe plate, thus forming a channel longitudinally thereof substantially in the same plane as the top sides of said toe-plate shank-extensions, and the underside of the shank-extensions of said heel plate, the latter extensions occupying said channel and having contact with the inner sides of said wings and lugs, and means for clamping said plates in adjusted position.

2. In a skate body as set forth in claim 1, the further addition of a plate riveted to said wings and lying over the shank extensions of said heel plate.

3. A member for a skate body embracing a toe-plate having a channel formed centrally longitudinally thereof on its upper side by pressing from said plate at each side thereof a side wing extending from the shank forwardly, and a lug longitudinally in alignment with said wing, and spaced apart therefrom, the sides of said channel being formed by the opposing inner edges of said wings and lugs, and a pair of spaced longitudinal shank-extensions integrally formed with said toe-plate, their upper surfaces being in the same plane as the upper surface of said channel.

WILLIAM HAMILTON DUNNE.
